BURNER CONTROLLING APPARATUS

Application filed August 11, 1930. Serial No. 474,544.

This invention relates to improvements in automatic control mechanisms for heating plants, and has among its objects; to provide means for initiating and timing two ignition periods, one before and one after burner motor activation; to provide a delayed re-trial re-ignition period after flame failure due to causes other than a call for less heat by the room thermostat; to time this delay period by cooling motion of a thermal element; to provide among other things a thermally operable device of the differential type which when in thermal equilibrium, conditions the control apparatus for starting when the room thermostat calls for heat, and which thermally operable device is adapted to be moved as a result of application of heat to close and initiate motor operation, and in which upon application of heat from a different source the starting contact, (which has closed as a result of thermal equilibrium) is opened to such a degree that a re-start is impossible except at the end of a timed period which is determined by the cooling motion of the timing element; and generally to provide means for automatically controlling a burner apparatus adapted to time pre and post ignition periods, and automatically stop the apparatus if flame is not produced, and lock it against automatic re-start.

Features of the invention include all of the circuit arrangements shown in the drawing and their equivalents, along with those broader aspects of the invention which relate to the automatic control including a pre-ignition period, and a post-ignition period or continuation of ignition for a predetermined time after ignition is produced, and the prevention of a re-ignition operation, except at the end of a predetermined interval, after flame extinguishment from any cause, except a call for less heat by the controlling temperature-responsive device, or its equivalent.

Features, objects and advantages of the invention will appear in the description of the drawing, forming a part of this application, and in said drawing

Figure 1 is a diagrammatic view of one

embodiment of the invention, which includes a thermal safety switch as a means for locking the apparatus against further operation, if flame is not produced at the end of the pre-determined ignition period;

Figure 2 is a fragmentary diagram showing a portion of the system and its modified arrangement of circuits; due to omission of the thermal safety switch or timing mechanism.

In the drawing, numerals 6 and 7 indicate the main power lines. Numeral 5 indicates the secondary of a transformer, the primary of which is connected across the lines at 6 and 7. 1 indicates a burner motor, and it is assumed that a suitable burner is controlled thereby, although not shown. Numeral 2 indicates what is herein termed a post-ignition means. Numeral 3 indicates what is herein termed a pre-ignition means. WRB represent the contacts of a room thermostat. Elements 8 and 24 represent a thermal safety switch which is adapted to open if flame is not produced at the end of any ignition timing period, and cause a shut down of the entire apparatus, and which is adapted to be locked in open position in the usual manner, although the locking arrangement has not been shown. There are three relays or equivalent devices employed, and they are respectively referred to as No. 1, No. 2 and No. 3. Their coils are respectively indicated at 11, 12 and 13. Relay No. 1 controls four contacts, 14, 15, 16, 17, and its closure, among other things, results in energization of pre-ignition means 3. Relay No. 2 controls three contacts, 18, 19, 20 and its energization results, among other things, in energization of motor 1 and post-ignition means 2. Energization of relay No. 2 is brought about by the motion of a thermal element (28-29 of the "differential" type) to switch closing position, due to application of heat by an electrically operable heating element 26 which is in the starting and holding circuits of No. 1 relay. This element 28-29 controls three contacts, 34, 35, 40. When relay No. 2 is energized, the heating coil 26 for the thermal device is shunted, and the thermal element cools, opening the contact which

55

100

was previously closed to obtain energization of relay No. 2. Relay No. 3 is controlled by a device 10 which closes a contact if flame is produced at the burner, and the relay in turn controls 3 contacts. Before energization, one contact controlled by this relay is closed and is in the starting circuit for No. 1 relay. On energization of No. 3 relay the thermal timer switch receives heat by means of a second electrically operable heating device 25, and begins a movement, at the end of which, the holding circuit for relay No. 1 will be broken. This relay No. 3 also controls a contact which shunts out the safety timer heating coil 24. The energization of No. 3 results in the de-energization of both ignition means 2 and 3, and continued operation of the burner motor 1. This operation normally takes place until the room thermostat opens its contacts BR, WR, conditioning the apparatus for a normal start including a trial ignition period, on a call for more heat at the room thermostat.

A more detailed description of the arrangement and functions of the parts, is given there below under the heading "Operation".

Operation

The operation is as follows: On closure of the room thermostat at W-R-B, relay No. 1 is energized through the following circuit: from one side of the secondary 5 of the transformer, thermal safety switch 8, W-R-B, contact 23 of relay No. 3, starting contact 35 of the timer switch, blades 32-28-29 (or their equivalents), heating coil 26, coil 11 of relay No. 1, to the other side of the secondary 5. Relay 1 is now energized and holding contact 14 is closed, contact 15 which controls energization of relay No. 2 is closed, contact 16 closes and the pre-ignition means 3 is energized, and contact 17 is closed to condition the post-ignition means for energization on closure of relay No. 2. Heating coil 26 is now receiving current, and the elements 29-28 are moving in a direction of arrow G, to close contact 40 at the end of a predetermined time, which is the pre-ignition period.

On closure of contact 40 relay No. 2 is energized through the following circuit: one side of secondary 5, thermal switch 8, W-R, contact 14 of relay No. 1, contacts 34, 40 of the timer switch, contact 15 of relay No. 1, heating coil 24 of the thermal safety switch, coil 12 of relay No. 2 to the opposite side of secondary 5. On closure of relay No. 2, a holding circuit for No. 2 relay is made as follows: 5, 8, W-R, contact 18 of relay No. 2, contact 15 of relay No. 1, coil 24, 12, to 5. Contact 19 also closes and shunts out timer switch coil 26.

The starting and holding circuits for No. 2 pass through the coil 24 of the thermal safety.

As before stated, when No. 2 closes, the pre-ignition timer heating coil is de-energized. The holding circuit is made for relay No. 2 which still passes through the thermal safety switch coil 24, as well as through a contact of No. 1 relay. This holding circuit is made so that although contact 40 opens, due to the cooling of the blade 29, as the result of de-energization of pre-ignition timer coil 26, the thermal safety switch coil 24 is still in circuit, and if flame is not produced at the end of a predetermined period the whole apparatus will be de-energized and the safety switch 8 will lock the device in the usual well known manner. Activation of the igniter for a timed period before feeding fuel is particularly desirable when ignition means of the hot wire or glow bar type is used. This type of ignition means is incapable of igniting oil until the igniter becomes red hot. However, when the glow bar is repeatedly heated to such high temperature it deteriorates very quickly whereas if it is only heated sufficiently to cause it to act as a vaporizer and not as an igniter, its life is prolonged. The glow bar is used for vaporizing the oil preparatory to ignition. The pre-ignition means is first energized and then the motor and post-ignition means 2 are energized simultaneously while the ignition means 3 continues to be active. A predetermined time after flame is established, and responsive to any suitable combustion responsive device or devices, both ignition means 2 and 3 are simultaneously de-energized.

The present invention includes a timed operation of ignition before oil is delivered (pre-ignition), and a timed operation of ignition (post-ignition period) after flame is produced, along with various safety and recycling features. In the present disclosure, glow bar and spark ignition can be used, if desired. If another type of ignition is desired, wherein one device will properly perform the igniting function, it is within the scope of this invention to eliminate the supplemental ignition means 2.

Assuming that flame is produced before the safety switch 8 opens, relay No. 3 will be energized as the result of closing of contact 10 of the pyrostat or flame responsive device. This closure results in energization of relay No. 3 and post-ignition timer coil 25. On energization of relay No. 3 the starting contact 23 for No. 1 is opened, and contact 21 is closed which shunts out the coil 24 of the thermal safety switch 8 (it is to be noted that the holding circuits are always first to be made, then the starting circuits). The holding circuit for No. 2 now passes through contacts 21 and 22 controlled by relay No. 3 and through the holding contact 18 for No. 2. The post-ignition timing operation is begun on energization of relay No. 3 and at the end of that period the holding contact for No. 1,

is broken at 34. Relay No. 1 falls out and the pre- and post-ignition circuits are broken. Relays No. 2 and 3 are, however, held in. If on a call for less heat, and opening of the contact W-R thermostat No. 2 relay is de-energized and the motor stopped. An interval, however, will elapse before relay No. 3 is de-energized, this interval being provided so that in case of flame failure, during normal 10 operation, there will be time allowed for dissipation of explosive gases before starting contact 23 is closed and therefore before recycling operation and reenergization of relay No. 1 can be had. Thus far, the normal operation 15 only has been described in which flame is continuous until there is a call for less heat at which time the entire apparatus is shut down until a call for more heat takes place. However, in case no flame is produced, during 20 an ignition period, switch 8 will be opened and locked, and the apparatus cannot function automatically until after inspection and repair.

The starting circuit for No. 1 relay is 25 through the thermal safety switch 8, also through contact 23 of the flame responsive relay No. 3, through the time switch (contact 35) and through the pre-ignition timer coil 26. The holding circuit for No. 1 relay is 30 also through the thermal safety switch 8 but contact 35 which is in the starting circuit for No. 1 relay, is shunted out. The holding circuit for No. 1 relay is as follows: one side of the transformer of safety switch 8, W, R, 35 to contact 14 of relay No. 1, contact 34, 33, 32, 28, 29, 26, 11 to opposite side of the transformer. This contact 35 is controlled by the thermal timing element 28, and is held open while flame is present (due to the heating 40 action of element 25). This contact closes to permit re-trial ignition after flame extinguishment only at the end of a timed period (controlled by the cooling motion of 28-29), to allow for dissipation of any explosive mixture in the fire box.

The starting circuit for No. 2 relay may be through either one of two paths. First, from source 5, switch 8, W-BR, contact 23 of relay No. 3, time switch of contacts 35-50 40, contact 15 of relay No. 1, heating coil 24 of thermal safety switch, to coil 12 of relay No. 2, thence to source 5. Or, second, source 5, switch 8, WR, contact 14 of relay No. 1, contacts 34-40, contact 15 of relay No. 1, 55 24, 12, to source 5.

After closure of No. 2, heating coil 26 is shunted out due to closure of contact 19 of relay No. 2, through the following circuit: 5, 8, WR, 14, 34, 28, 29, 19 to 11, to 5. Contact 18 of relay No. 2 is closed and is adapted to maintain the circuit of relay No. 2 closed after No. 1 is opened, provided No. 3 is closed, and maintains a closed circuit independently of contacts 40-34. This circuit 65 is as follows: 5, 8, W, R, 18, 22, 21, 12 to 5.

On energization of No. 2 relay, the motor and post-ignition are energized.

On energization of No. 3 relay due to production of flame and due to closure of flame switch contact 10, contacts 21 and 22 are 70 closed. Contact 21 establishes a holding circuit for relay No. 2 which does not include the coil 24. In other words, the closure of contact 21 shunts out coil 24. At this time a holding circuit at contact 22 is established 75 for No. 2 relay which is independent of contact 34, which contact will be opened at the end of a predetermined interval after the closure of No. 3 relay. The holding circuit for No. 2 can now be traced from 5 through 80 8, W, R, 18, 22, 21 to 5.

The thermally operable timer switch diagrammatically indicated herein as composed of two sets of bi-metallic elements 28-29, 85 may be of any preferred form. As a matter of fact the device used is somewhat more complicated than that diagrammatically illustrated. Any equivalent device may be used, which, upon application of heat moves, and at the end of a predetermined time closes the starting contact of relay No. 2, and which on energization by another heater as result of closure of the flame responsive device, moves the element to open the contacts 35-34. It 90 will be noted that when the elements 28 and 29 are in thermal equilibrium, contacts 34-35 are closed and contact 40 open. Upon application of heat at 26 element 29 warps in the direction shown by arrow G, and contact 40 is closed at the end of a predetermined 95 time. When 26 is de-energized as result of closure of No. 2 relay, on cooling of element 29 the elements 28-29 move in the direction of the arrow H in an opposite direction to open the contact 40, and on application of heat through element 25 element 28 warps and this motion is continued in the same direction and at the end of a timed period contacts 35-34 are opened. Heating of 100 25 is, however, continued beyond this point and 105 in fact continues as long as flame is present and as long as contact 10 is closed. It results that during normal operation or flame period of the burner, the elements 32-33 are held in spaced relation to contacts 34-35 as the result of continued application of heat. Therefore, on flame failure and resultant de-energization of coil 25, contacts 34 and 35 110 will not be again made until after a predetermined time interval obtained by a cooling movement of element 28 in direction of the arrow G. Thus, before a re-start or re-trial ignition period can be initiated, sufficient time elapses for the dissipation of explosive gases from the fire box, by natural 115 draft, or otherwise.

Thus means is provided (relay No. 1 or its equivalent) which is energized on a call for heat and closes the pre-ignition circuit, as well as a contact which is in the post ignition 120 125 130

circuit. This relay energization is made through a circuit which includes thermal safety switch 8, a contact 23 of relay No. 3 (closed when flame is absent), timer switch 5 contact 35 (closed when blade is in equilibrium) and the pre-ignition timer coil 26. No. 2 relay controls the motor 1 and post-ignition means 2, and energizes when the timer contact 40 closes at the end of a pre-10 ignition period as determined by the heating motion of the thermal element 29 by timer coil 26. No. 2 relay is energized by a circuit which passes through the thermal safety switch 8, WR, contact 14 of relay No. 1, and 15 timer switch, contacts 34, 40, contact 15, heater 24, and coil 12, or by circuit 8, WRB, 23, 35, 40, 15, 24 to 12. When No. 2 relay energizes, it establishes a holding circuit for itself independently of timer switch contact 20 40, as follows: 8, WR, 18, 15, 24, 12 to 5.

It should be noted that one timer switch contact 40 is closed by heating motion initiated by a call for heat, and that the other two timer switch contacts 35, 34 are successively 25 opened as a result of heating motion initiated by production of flame. It should further be noted that contacts 35, 34 are maintained in open position as a result of continued application of heat (through coil 25) while the 30 burner is producing flame. On flame failure, some appreciable amount of time is therefore required for these last two contacts to close, as result of a cooling motion to control element 28.

35 It is conceivable that a circuit which falls within the purview of this invention, may be one in which the thermal safety switch 8 and its timer coil 24 are omitted. In this 40 instance, see Fig. 2, there is no necessity for shunting out the coil 24 and therefore contact 21 is omitted. There will be no change in the circuit for relay No. 1, but when relay 45 No. 3 is energized, the holding circuit for No. 2 relay will be only through contact 18 of relay No. 2 and contact 21 of relay No. 3. This explanation is made, because it is conceivable that the invention herein may be applied to systems in which it is unnecessary to provide an electro-thermally operable safety switch, which locks the system against 50 automatic operation if ignition is unsuccessful.

Reverting the timing feature:

55 In the first instance a heating motion closes one of the timer switch contacts (40). In another instance the heating motion breaks two of these contacts, (35, 34) and continued heating motion of element 28 in direction of 60 arrow H, separates the contact or contacts, so that closure of these contacts for a re-start is timed by a cooling motion, making it impossible to energize the ignition means until after a predetermined time, at the end 65 of which there will no longer be sufficient

residual fuel in the fire box to cause explosion as a result of re-trial ignition.

In this device every low voltage circuit passes through the thermal safety switch 8. It is also to be noted that on a call for heat 70 the starting circuit passes through elements WRB of the room thermostat. However, if other relays are employed, as in the present case, contacts WR only of the room thermostat are used for controlling the starting as 75 well as the holding circuits of these additional devices.

It is again to be noted that in this device, when flame fails while the room thermostat is calling for heat, the motor is shut down immediately that the flame-operated switch 80 10 opens; a very important feature. Moreover, re-trial ignition cannot take place until explosive gases are dissipated; another important feature.

In certain controls heretofore used, after a flame failure, the burner would not perform a trial ignition or starting operation or cycle, but the burner would simply operate for about two minutes, without ignition 90 and with no flame, and with oil being supplied, and then the device would be locked against further automatic operation. The same thing would happen if flame was extinguished immediately after ignition was discontinued at the end of the trial ignition period. This arrangement had certain disadvantages. Under these conditions the refractory was hot and on reestablishment of 95 the ignition, explosion would take place. In the present device, it is impossible to re-start the apparatus, after flame failure while the room thermostat is calling for heat until after a timed interval during which dangerous explosive mixtures are dissipated by the natural draft of the furnace.

100 We claim as our invention:

1. In combination, a burner apparatus including a burner and burner motor and ignition means, and means adapted to control the motor and ignition means to activate said ignition means for a predetermined time before burner motor activation, and then continue ignition means operation, said means including a thermally responsive switch of the differential type adapted when in thermal equilibrium to permit activation of said ignition means on a call for heat, and means operable after ignition activation to move 110 said thermal element to close a circuit which results in activation of the motor and continued activation of said ignition means, and means responsive to production of flame at the burner operable after burner activation to initiate a timed movement of said thermal switch at the end of which said ignition means is de-activated, and motor activation 115 continued, and re-activation of said ignition means is prevented until after a predetermined time.

mined interval of time, following flame failure, after successful ignition.

2. In combination, a burner apparatus including a burner and burner motor, pre-
5 ignition means, post-ignition means and means adapted to control the motor and ignition means to activate said pre-ignition means for a predetermined time before burner motor activation, and then activate
10 said post-ignition means and maintain activation of said pre-ignition means, said means including a thermally responsive switch of the differential type adapted when in thermal equilibrium to permit activation of said pre-
15 ignition means on a call for heat, and means operable on pre-ignition activation to move said thermal element to close a circuit, which results in activation of said post-ignition means and motor, and means responsive to
20 production of flame for initiating a timed movement of said thermal element at the end of which both ignition means are deactivated, and prevent re-activation of said ignition means until after a predetermined
25 interval of time, following flame failure.

3. In combination, a burner apparatus and a burner motor, ignition means, means adapted to activate said ignition means for a predetermined period of time before motor
30 activation, means adapted to activate the motor at the end of said timed period, and to continue ignition means activation thereafter, and means operative as a result of production of flame to effect de-activation of
35 said ignition means at the end of a second timed period and to thereafter continue motor activation.

4. In combination, a burner apparatus and a burner motor, ignition means, means adapted to activate said ignition means for a predetermined period of time before motor activation, means adapted to activate the motor at the end of said timed period, and to continue ignition means activation thereafter, and means operative as a result of production of flame to effect de-activation of said ignition means at the end of a second timed period thereafter and to continue motor activation, and to prevent re-activation of the
50 ignition activating means for a predetermined length of time after flame failure following successful combustion.

5. In combination a burner apparatus and a burner motor, first and second ignition
55 means, means adapted to activate the first ignition means for a predetermined timed period before motor activation, means adapted to activate said motor at the end of said time period, and to activate said second ignition means and thereafter continue activation of both ignition means, and motor, and means operative as a result of production of flame and at the end of a time period, to effect de-activation of both ignition means but con-
60 tinue motor activation.

6. In combination a burner apparatus and a burner motor, first and second ignition means, means adapted to activate the first ignition means for a predetermined timed period before motor activation, means adapted to activate said motor at the end of said time period, and to activate said second ignition means and thereafter continue activation of both ignition means and motor, and means operative after production of flame and at the end of a time period after flame production to effect de-activation of both ignition means but continue motor activation, and also operative to prevent re-activation of the first mentioned means for a predetermined length of time after flame failure following successful combustion.

7. A device of the class described including a burner and a burner motor, ignition means, means adapted to activate said ignition means for a predetermined time before motor activation, means adapted to activate said motor at the end of said timed period and continue motor and ignition means activation, means responsive to production of flame at the burner and adapted to de-activate said ignition means at the end of a time period after flame is produced and continue motor activation, and means effective to discontinue operation of the ignition means and motor if flame is not produced at the end of a predetermined time period, following motor activation.

8. A device of the class described including a burner and a burner motor, ignition means, a room thermostat, an ignition timer switch controlling first, second and third contacts, first and second electrically operable means for effecting motion of the timer switch, a first relay operable when energized to energize the ignition means, a second relay operable when energized to energize the motor, a third relay, means operable to energize said third relay as the result of production of flame at the burner; a starting circuit for the first relay including therein the room thermostat, a contact of the third relay which is closed when the relay is de-energized; the first contact of said ignition timer switch, and said first timer switch motion effecting means; a holding circuit for said first relay, having therein said room thermostat, a holding contact controlled by said first relay, the second contact of the timer switch, and said first timer switch motion effecting means; said first timer switch motion effecting means maintaining closed the first and second timer switch contacts and closing the third timer switch contact; a starting circuit for said second relay, having therein said room thermostat, said holding contact of the first relay, the second and third contacts of said timer switch, and a second contact of the first relay; said second relay on energization shunting out said first timer switch motion

effecting means; a holding circuit for said second relay, which has therein said thermostat, a holding contact controlled by said second relay, and said second contact controlled by said first relay; said third relay being in a circuit through said second timer switch motion effecting means, and having contacts which upon energization of the relay establish a holding circuit for the second relay through said room thermostat, which circuit is independent of the contacts controlled by the first relay, said second timer switch motion effecting means when energized causing opening of said first and second timer switch contacts.

In witness whereof, we have hereunto set our hands this 30th day of July 1930.
